IDENTIFICATION TAG WITH CLINCH LOCK

Arthur A. Pannier, Salt Lake City, Utah

Application October 22, 1935, Serial No. 46,058

5 Claims. (Cl. 40—3)

This invention relates to an identification tag provided with a clinch lock, and belongs in general to the type largely used in identifying livestock although it may be used for many other purposes. When used for identifying animals, tags of this type are attached to the ears and are therefore commonly known as ear tags.

Identification tags of the present type consist in general, of two branches connected to each other and disposed in mutual opposition. One of the branches has a tongue extending transversely thereof, and this tongue has a sharp point which pierces the object to which the tag is attached. After piercing the object, the point continues through an opening in the other branch of the tag, and is bent around or clinched on the outside of the other branch. Such a clinch as ordinarily formed, often gives way when stressed, especially in cases where the tags are attached to animals' ears, thereby causing loss and confusion, since identification in determining ownership of the animals is destroyed.

In my improved tag, a barb or abutment portion is provided at the rear of the point, and this barb, due to contact with a properly shaped portion of a plier jaw, is caused to slip automatically into place against some portion of the opposite branch, usually the outside surface thereof, during the process of clinching the tongue. The barb or abutment prevents opening, unless the tag structure is distorted.

In the drawing,

Fig. 1 represents the plan of a tag in the flat form, before it is bent around into shape ready for attaching;

Fig. 2, a side elevation thereof, partly in section taken on the line 2—2 in Fig. 1;

Fig. 3, a side elevation, partly in section, showing a shaped tag as it is held in the jaws of a pair of special ear-tag pliers just previous to attaching the tag;

Fig. 4, a fragmentary elevation, partly in section, drawn to an enlarged scale, and showing the tag closed, with point clinched and locked.

Referring to the drawing, the numeral 10 in Figs. 1 and 2, indicates a tag in the strip or flat form, before it is bent into shape for attaching. At one end, the tag is provided with a tongue 12 having the point 14 with the tip 15 and the barb or abutment portion 16. At the other end of the tag strip is an opening 17, and spaced slightly apart therefrom, is another smaller opening or indenture 18, these openings being similar in certain respects to those provided in tags of prior construction.

Before attaching the tag, it is bent into the general form having the branches 10—1 and 10—2, Fig. 3, which are connected to each other by a bent portion at the rear of the leg. The tongue 12 extends transversely and inwardly from one of the branches, in this instance, branch 10—2. In this form, the tag is inserted in a pair of special pliers having the jaws 19 and 20, ready for applying it in substantially the customary manner. When the jaws of the pliers are closed together, the point 14 passes through the opening 17 and is bent around in the curved recess 21 of the plier jaw 20, leaving the point clinched as indicated at 14—1 in Fig. 4. The mere clinching of the point, in general, is also in accordance with well known practice, a difference in the present invention being, that the barb 16 slips automatically into an angular niche 24, formed partly by the forward portion of the recess 21 and partly by the upper flat surface of the tag branch 10—1, leaving the clinched point locked with its barb or abutment portion 16 projecting over a lip 25, the latter constituting in this instance, an upper edge of the opening 17.

When the tongue is thus clinched, the barb 16 protrudes from the base of the point 14 and is directed towards the front of the branch 10—1, while the abutment face of the barb has a secure hold on the keeper-face, the latter preferably coinciding with the outer surface of the branch 10—1. Any stress tending to separate the two branches 10—1 and 10—2, as indicated by the double-pointed arrow in Fig. 4, results in distorting the tag structure rather than in merely unfastening the clinch.

It is desirable that the point or tip of the clinched tongue be braced and sheathed, and this is accomplished by causing the point or tip of the closed or clinched tag to be disposed in the opening or indenture 18, Fig. 4. Sheathing of a point tip is common, but in this instance embraces a new feature which consists in bracing the tip against the rear face of the opening 18 so as to prevent inadvertent backward movement of the barb 16.

It should be clear that I do not claim broadly an identification tag consisting merely of two opposing members connected to each other at one end and held together at the other end by means of a tongue having a clinchable point, but only when the tongue of such a tag is provided with an abutment lock which is so constructed that pressure exerted on the fore part of the tongue causes the said lock to be pushed backward into engagement with the superficial

surface of the opposing branch, as clearly indicated in Fig. 4, where the sheathed tip holds the lock in such engagement.

Having fully described my invention, what I claim is:

- 5 1. An identification tag, including in combination, two connected branches capable of being closed together, a tongue extending inwardly from one of the branches, a clinchable point at 10 the end of said tongue, said clinchable point having a tip at the forward end and an abutment at the rearward end; and a perforated portion at the free extremity of the other branch, the said clinchable point being adapted to pass 15 through the perforated portion for clinching, and sheathing means disposed in proximity to the perforated portion so as to receive and sheath the tip of the tongue when clinched, the closed form of the tag being such, that the said abut- 20 ment is substantially in coincidence with and overlapping, the outer surface of the said other branch, while the sheathed tip is effective to normally prevent the abutment from being moved relative to its overlapping position.
- 25 2. A clinched identification tag, including in combination, two connected branches disposed in mutual opposition to each other, a tongue protruding inwardly from one of the branches and clinched on the outer side of the other branch, 30 the said other branch having an aperture to receive the tongue, a point integral with the said tongue, a tip at the forward end of the point, an abutment at the rear of the said point, and sheathing means on the other branch for the purpose 35 of sheathing the said tip, the said abutment being in locked engagement with a portion of the other branch in such relation that the sheathed

tip normally prevents the abutment from becoming disengaged.

3. An identification tag, including in combination, a member having a perforation, a second member connected to and opposite the first mentioned member, a clinchable portion extending from the second member through the said perforation, sheathing means in the first mentioned member and in proximity to the said perforation, the forward end of said clinchable member being sheathed within the said sheathing means, and an abutment lock on the said clinchable member, said lock being normally held in engagement with the said second member by means of the 15 sheathed forward end.

4. An identification tag comprising two branches connected to each other at the rear thereof, one branch having an aperture near the front end thereof, a keeper-face portion in proximity to the aperture, a tongue at the front end of the other branch and extending through the aperture in the said one branch, the said tongue having a point portion with a tip at the outer end thereof, a barb protruding from the base of the point portion and directed towards the front of the other branch, the said barb having an abutment face disposed to engage the keeper-face, and bracing means effective against the tip of the point for the purpose of normally holding the said abutment face in engaging relation with the said keeper-face.

5. An identification tag in accordance with claim 4, wherein the keeper-face coincides substantially with the outer surface of the said one branch.

ARTHUR A. PANNIER.
